UNITED STATES PATENT OFFICE

154,006

DESIGN FOR A KNIFE OR SIMILAR ARTICLE

Franz Wagner, Chicago, Ill., assignor to Ekco Products Company, Chicago, Ill., a corporation of Illinois

Application July 17, 1948, Serial No. 147,647

Term of patent 14 years

(Cl. D54—12)

To all whom it may concern:

Be it known that I, Franz Wagner, a citizen of the United States, residing at Chicago, county of Cook, State of Illinois, have invented a new, original, and ornamental Design for a Knife or Similar Article, of which the following is a specification, reference being had to the accompanying drawing, forming part thereof.

Fig. 1 is a side elevational view of a knife, showing my new design.

Fig. 2 is a top view thereof.

Fig. 3 is a bottom view thereof.

Figs. 4 and 5 represent enlarged sectional views taken on line 4—4 and line 5—5, respectively of Fig. 1.

I claim:

The ornamental design for a knife or similar article, as shown.

FRANZ WAGNER.
